UNITED STATES PATENT OFFICE.

EDWARD P. DEAN, OF ASHLAND, OHIO.

BLACKBOARD-ERASER.

No. 890,342.

Specification of Letters Patent.

Patented June 9, 1908.

Application filed June 28, 1907. Serial No. 381,280.

To all whom it may concern:

Be it known that I, EDWARD P. DEAN, a citizen of the United States, residing at Ashland, in the county of Ashland, State of Ohio, have invented certain new and useful Improvements in Blackboard-Erasers; and I do hereby declare the following to be a full, clear, and exact description of the invention, such as will enable others skilled in the art to which it appertains to make and use the same.

This invention has relation to blackboard erasers, that are employed to clear the face of the board from chalk or crayon lines or marks made thereon.

Various problems are presented in the production of an eraser of the character described that will overcome all difficulties and objections thereto. In the first place, the erasure of the chalk or crayon marks necessitates the removal of the dust or particles forming the said marks from the board. If the eraser only brushes the dust off the board, it is simply thrown into the atmosphere and becomes a menace to the health of scholars and teachers. If the dust is taken up in the eraser, it must be frequently freed from the latter or it will soon become inefficient. Other points, such as noiselessness, durability, readiness of use, and entire efficiency are encountered.

It is the object of my invention to provide an eraser that will at once overcome the objections and mischiefs mentioned and enhance the efficiency of the device in various desirable respects.

The nature of the invention is fully and clearly ascertainable from the device portrayed in the annexed drawings, forming a part of this specification, in view of which it will first be described with respect to its construction and mode of use, and then be pointed out in the subjoined claim.

Of the said drawings—Figure 1 is a perspective view of the invention. Fig. 2 is a transverse section.

Similar characters of reference designate similar parts or features, as the case may be, wherever they occur.

In the drawings, 4 designates the edges; 5, the sides, and, 6, the ends of the eraser. As the edges, 4, are employed to rub the board the eraser may be said to be double or of dual

character—that is, it presents two efficient erasing faces, both of which may be used.

In the construction of the eraser, I employ alternate strips of high-grade firm wool felt and narrower strips of wood, the former extending to the ends of the latter and a very considerable distance beyond the sides thereof. The said layers or strips may be as many in number as may be necessary to form an eraser of the required size, and they may be connected or secured together in any suitable manner. As herein shown, the device is formed from four strips of felt, B, with three intermediate strips of wood, A; the strips of felt being secured to the sides of the strips of wood by cement, and the entire structure bound firmly and compactly together by a band, 7, passed centrally around the ends and sides and secured in that position.

Inasmuch as the sides of the wood strips A are not coextensive with the same portions of the felt strips, the margins of the latter are maintained in spaced relationship, as shown at 8 in the drawings.

The strips A of wood will, of course, be relatively thin, and since they are employed to space the margins of the strips of felt and impart stiffness and compactness to the body, it would not be a material departure from my invention to form them from other material than wood, nor to make one or more of the said strips of metal.

In use, the edges 4, will, be used to erase the marks on the board, and the dust wiped off by the felt strips will be collected in the interspaces 8 and not be thrown off into the atmosphere, and as the two edges, 4, can be used the eraser can be employed for quite a long period before it becomes so filled with dust as to be made inefficient, and when the time comes to renovate the device it can be taken to some out-of-the-way place and cleaned by jarring the ends 6 on a stationary object, running a stick through the interspaces 8, and brushing or wiping off the felt edges and ends.

It is obvious that the device is noiseless in character, so that if it should happen to fall upon the floor it would not disturb or annoy any one.

It is also apparent that the invention can be easily and economically constructed and

that it will be of quite a durable nature, and in all respects desirable.

What is claimed is—

5 A blackboard eraser comprising alternate strips of felt and wood secured firmly together the strips of felt extending at their opposite edges beyond the strips of wood leaving dust-collecting interspaces between the layers of felt at their margins, and a stout

band passed centrally about the ends and 10 sides of the device between their opposite edges.

In testimony whereof, I affix my signature, in presence of two witnesses.

EDWARD P. DEAN.
